UNITED STATES PATENT OFFICE.

EMIL GOETZE, OF WALLINGFORD, CONNECTICUT, ASSIGNOR TO SAMUEL L. BARBOUR, OF HARTFORD, CONNECTICUT.

DESIGN FOR A CANDLESTICK.

SPECIFICATION forming part of Design No. 35,786, dated March 4, 1902.

Application filed February 6, 1902. Serial No. 92,924. Term of patent 7 years.

To all whom it may concern:

Be it known that I, EMIL GOETZE, a citizen of the United States, and a resident of Wallingford, in the county of New Haven and State of Connecticut, have invented and produced a new and original Design for a Candlestick, of which the following is a specification, reference being had to the accompanying drawings, forming part hereof.

10 Figure 1 is a perspective view of a candlestick embodying my design. Fig. 2 is a plan view of the base of the article.

The structure in which my design is embodied includes as an essential feature a base 15 *a*, provided with feet *b*, arranged at intervals about the base, the surface of which displays prominent projections *c* and a wrinkled or wavy effect, (denoted at *d*.) Above the base is a stem *e*, which expands into a column in 20 wavy outlines and having on its surface a number of folds *f*, which form long narrow projections. The top *g* of the column displays at the bottom part a series of knobs ar-

ranged at intervals, and the surface of the structure at this part is also disposed in folds 25 of varying outlines. Above the column and supported by a narrow neck *i* is an enlargement *k*, with surface ornamentation near its base and flaring at its upper part, where it terminates in a broadened member characterized 30 by irregular outline, as seen in plan view. A wavy surface disposed in folds and prominent knobs characterizes this part of the structure as to its design.

Having described my invention, what I 35 claim as new, and desire to secure by Letters Patent, is—

The design for a candlestick as herein shown and described.

In witness whereof I have hereunto signed 40 my name to this specification in the presence of two subscribing witnesses.

EMIL GOETZE.
